(57) **CLAIM**

The ornamental design for a folding portable toilet, as shown and described.

DESCRIPTION

FIG. 1 is an upper-front perspective view of a folding portable toilet in an open configuration and the lid in a down/closed position according to the present invention. FIG. 2 is an upper-front-right view of the folding portable toilet of FIG. 1.

FIG. 3 is an upper-back-left view of the folding portable toilet of FIG. 1.

FIG. 4 is an upper-left view of the folding portable toilet of FIG. 1.

FIG. 5 is a top-down view of the folding portable toilet of FIG. 1.

FIG. 6 is a back view of the folding portable toilet of FIG. 1.

FIG. 7 is a bottom-up view of the folding portable toilet of FIG. 1.

FIG. 8 is a front view of the folding portable toilet of FIG. 1.

FIG. 9 is a left view of the folding portable toilet of FIG. 1.

FIG. 10 is a right view of the folding portable toilet of FIG. 1.

FIG. 11 is an upper-back-left view of the folding portable toilet of FIG. 1 with the lid open and the child seat in a ready-to-use position.

FIG. 12 is an upper-back-left view of the folding portable toilet of FIG. 1 with the lid and child seat open and the adult seat in a ready-to-use position.

FIG. 13 is an upper-back-left view of the folding portable toilet of FIG. 1 with the lid, child seat and the adult seat open.

FIG. 14 is a back view of the folding portable toilet of FIG. 1 in a closed/folded configuration.

FIG. 15 is a bottom-up view of the folding portable toilet of FIG. 1.

FIG. 16 is a front view of the folding portable toilet of FIG. 1.

FIG. 17 is a left view of the folding portable toilet of FIG. 1, the right view being significantly reciprocal of the left view; and,

(Continued)

FIG. 18 is a top-down view of the folding portable toilet of FIG. 1.
